UNITED STATES PATENT OFFICE.

EZRA L. DEANE, OF HOLYOKE, MASSACHUSETTS.

ADJUSTABLE HEAD FOR T-SQUARES.

SPECIFICATION forming part of Letters Patent No. 349,697, dated September 28, 1886.

Application filed February 20, 1886. Serial No. 192,625. (No model.)

To all whom it may concern:

Be it known that I, EZRA L. DEANE, a citizen of the United States, residing at Holyoke, in the county of Hampden and State of Massachusetts, have invented new and useful Improvements in T-Squares, of which the following is a specification.

This invention relates to improvements in T-squares, the object being to provide a square of this class with an improved adjustable head-bar; and the invention consists in the peculiar arrangement of parts, as hereinafter fully described, and set forth in the claims.

In the drawing, forming part of this specification, is illustrated in plan view a T-square (the lower end of the blade being shown broken off) constructed according to my invention.

In the drawing, A is the blade, and B is the head, of the square, made of either wood or metal, said head and blade being rigidly secured together, as shown.

D is a head-bar pivotally attached by one end to one end of the head B by a link, c, the ends of the latter being attached to the said head and bar by screws, as shown. Said link and the below-described head and bar connections are of sufficient length to sustain the bar D, somewhat removed from the edge of the head B, so that the bar may have a free swinging movement toward and from the adjoining edge of said head. The end of the bar D opposite that which is connected to the head B by said link has a metallic arm, e, secured thereto, which projects beyond the end of the bar, and has the screw-threaded rod o pivotally secured to it and extending opposite the end of the head B, as shown, and said rod is provided with an adjusting-nut, v, and with a set-nut, w. The end of the head B is provided with a bifurcated arm, e', secured thereon opposite said arm e, and, like the latter, projecting beyond the end of said head, and the bifurcated portion of arm e' spreads sufficiently to admit said adjusting-nut v therebetween, and the said rod o passes transversely through said bifurcated parts of arm e' and nut v, and the said set-nut w is screwed on the end of said rod o, as shown.

It is well known that wooden T-squares are seldom accurate and require frequent adjustment, and the above-described improvements provide convenient and efficient means for adjusting a square to correct its angles. By turning nut w toward the end of rod o the latter is made free to be moved, together with the end of bar D, to which it is connected, by turning the said nut v, thereby swinging said bar until its edge is brought exactly at right angles to the edge of the blade A, or swinging said bar to a position relative to the head, other than at a right angle thereto, and when the bar is brought to the desired position the set-nut is screwed against arm e', locking the rod o to said arm. The nut w may be omitted, if desired, but without it the bar D may become inadvertently moved out of adjustment by the too easy rotation of the nut v.

What I claim as my invention is—

1. The combination, with the head B of a T-square, and with the head-bar D, pivotally connected by one end to said head, of an arm, e, on said bar opposite its pivoted end, having a screw-rod attached thereto, an arm, e', on said head opposite the arm on said bar, having a bifurcated end through which said screw-rod passes, and an adjusting-nut operating on said rod between the bifurcated parts of said arm e', substantially as set forth.

2. In combination with the head B of a T-square, the head-bar D, pivoted by one end to one end of said head B, the screw-rod o, and the adjusting-nut v, having an engagement with the ends of arms, substantially as described, on the ends of said head and bar, substantially as set forth.

3. In combination, the head B of a T-square having the bifurcated arm e' thereon, the swinging head-bar D, having the arm e thereon, the screw-rod o, connected to the latter and passing through arm e', and the nuts v and w, substantially as set forth.

EZRA L. DEANE.
